UNITED STATES PATENT OFFICE.

SAMUEL S. BLOOM, OF PHILADELPHIA, PENNSYLVANIA.

ARTIFICIAL-TOOTH MOUNT.

No. 897,518.

Specification of Letters Patent.

Patented Sept. 1, 1908.

Application filed January 3, 1908. Serial No. 409,189.

To all whom it may concern:

Be it known that I, SAMUEL S. BLOOM, a citizen of the United States, residing at Philadelphia, in the county of Philadelphia and State of Pennsylvania, have invented certain new and useful Improvements in Artificial-Tooth Mounts, of which the following is a specification.

This invention relates to artificial teeth and has for its object the provision of improved means which permit the dentist to conveniently and securely attach the artificial tooth or front, made of porcelain or other suitable material, to the metallic back-15 ing or plate by means of which the denture is secured in position.

While my present invention is capable of being employed in connection with various forms of artificial teeth, I have illustrated in 20 the accompanying drawings only an incisor. But it is to be understood that I do not limit myself to the special form shown.

Heretofore, in the manufacture of artificial teeth which have plates or backs to which the 25 porcelain fronts are secured, it has been common to mold and bake the porcelain tooth with a vertical recess in which the pin or rib carried by the back plate is cemented. It is practically impossible to complete the 30 tooth by the molding and baking operation with a correctly formed recess which is to receive the pin; and it has therefore been customary to drill out the recess so that the pin will fit snugly. In practice, a partially 35 formed recess is molded, and the correct form is given thereto by the use of a diamond drill after the tooth has been baked. This is not only an expensive operation due to the cost of the drills and the time required in drilling, 40 but it is almost impossible to drill out the recesses with uniform accuracy. The drill is liable to go too deep or not far enough, or to ream out the recess not in the exact lateral position which it should have. The especial 45 object of my present invention is to provide a construction which will insure accuracy in the shape and location of the recess in the tooth body after the baking operation.

To these ends the invention consists in the 50 construction and combination of parts substantially as hereinafter described and claimed.

Of the accompanying drawings:—Figures 1 and 2 are relatively an elevation and a 55 longitudinal section, on a larger scale, of one form of tooth to which my invention is

adapted. Fig. 3 represents a cross section on line 3—3 of Fig. 2. Figs. 4 and 5 are views similar to Fig. 3 and illustrating other cross sectional forms of the longitudinal 60 recess and lining. Fig. 6 is a sectional view, on a larger scale than Fig. 3, of the plate and rib and pin.

Similar reference characters indicate the same or similar parts in all of the figures of 65 the drawings.

The tooth body 10 is molded with a longitudinal recess having a lining 11 which may be of platinum or other suitable refractory material. The lining is in the form of a split 70 tube, but it is to be understood that by the word tube, I do not limit myself to one which is circular in cross section. It may be rectangular or somewhat dovetailed in shape. But it must be split or open along the side 75 which is to communicate with the open side of the recess of the tooth body. Said lining will be, in practice, supported in the mold in any suitable way during the molding and baking operations. When the porcelain body 80 is finished, its longitudinal or vertical recess is provided with a lining in proper shape in cross section to receive a correspondingly shaped pin which is carried by the plate.

Owing to the fact that the lining must be 85 in a position a little away from the rear face of the tooth body so that sufficient strength will be possessed by the latter at the edges of the vertical opening, it is essential that the pin 12 shall be carried by the plate 13 at a 90 slight distance therefrom. That is, it would not do to employ a perfectly flat plate and to secure the pin directly in contact therewith, as there would then not be sufficient space in the angular recess at each side of the 95 pin to permit the tooth body to slip to proper position. In order to make the pin stand a little away from the plate when secured thereto, the plate is struck up so as to form a slight rib 14 the upper surface of which is 100 properly formed to render it certain that when the pin is fastened to said rib they will be in proper alinement. When a pin which is circular in cross section is employed, the upper face of the rib is slightly concaved to 105 receive the convex side of the pin as shown in Fig. 6. This shape co-acts with the solder when the latter is applied, to form a durable connection between the plate and pin. If the pin is angular in cross section the face of 110 the struck up rib may be similarly formed. As above stated, the lining used in the tooth

body is to have a shape in cross section corresponding to the cross section of the portion which stands away from the plate.

When the dentist connects a properly shaped and properly shaded tooth body to the plate he usually employs cement to secure the end of the pin in the recess of the tooth body. But if he finds that a particular patient generates a saliva acid which is liable to dissolve the cement he may employ a soft solder. This could not be done with a tooth having no metal lining since the solder would not adhere properly to the wall of an unlined recess in a porcelain tooth. But of course it will be understood that the teeth are not sold or furnished with pins already soldered in the recesses.

Preferably I furnish the connected pins and plates with the pins of a length projecting considerably beyond the plates, which pins can be left full length or can be cut off by the dentist according to the use to which he intends to put the tooth. For crown work or "pivot" teeth, the pin will be left so that it can be secured in the drilled cavity in the root. For bridge work, the pin will be cut off by the dentist. The pin may be roughened or corrugated and may be given any suitable shape in cross section so that it can be firmly secured in a drilled root cavity without liability of turning. If a patient has entirely lost a tooth next to one which has to have a crown applied thereto, the plate car-

rying the pin may be of sufficient width so that said plate may carry not only the "pivot" tooth or crown but also one or more adjacent complete artificial teeth, thus forming a combination pivot and bridge device.

As shown in Fig. 2, the tooth is formed with a ledge 15 against which the lower edge of the plate abuts. In practice this ledge is so formed, relatively to the length of the lined recess, that the edge of the plate abuts against the said ledge as the end of the pin reaches the bottom of the lined recess. This affords additional support for endwise pressure instead of depending entirely upon the bottom of the recess bearing against the lower end of the pin.

Having now described my invention, what I claim is:—

1. A back plate for an artificial tooth mount having a portion thereof struck up to form a rib, and a pin secured to the upper face of said rib.

2. A back plate for an artificial tooth mount having a portion thereof struck up to form a rib, and a pin secured to the upper face of said rib, the face of said rib being depressed to receive a portion of said pin.

In testimony whereof I affix my signature, in presence of two witnesses.

SAMUEL S. BLOOM.
